The ornamental design for a power supply housing, as shown and described.

DESCRIPTION

FIG. 1 is a perspective view of a power supply housing showing our new design;

FIG. 2 is a right side elevational view thereof, the left side elevational view thereof being a mirror image;

FIG. 3 is a top plan view thereof;

FIG. 4 is a front elevational view thereof;

FIG. 5 is a rear elevational view thereof; and,

FIG. 6 is a bottom plan view thereof.

The broken lines in FIGS. 1, 3, 5 and 6 are included for the purpose of illustrating holes in the article, per se, in which the design is embodied and form no part of the claimed design.
